(57) **CLAIM**

The ornamental design for a game piece, as shown as described.

DESCRIPTION

FIG. 1 is a top, front isometric view of a game piece showing our new design.

FIG. 2 is a top plan view thereof.

FIG. 3 is a bottom plan view thereof; and,

FIG. 4 is a front elevational view thereof, the rear, right side and left side elevational views are a mirror image thereof. The broken lines in the figures are for illustrative purposes only and form on part of the claimed design.
